COVERED LADLE

Max W. Goldberg and Wallace W. Drissen, Port Washington, Wis., assignors to Modern Equipment Company, Port Washington, Wis., a corporation of Wisconsin

Application April 11, 1936, Serial No. 73,829

11 Claims. (Cl. 22—81)

This invention relates to improvements in covered ladles. Heretofore, in foundry practice, it has been customary to utilize relatively small sized ladles which hold only a limited quantity of molten metal. Necessarily, therefore, these ladles must be frequently refilled and a large number kept in constant use in order to handle mold requirements. Thus, a relatively large number of attendants are needed to take care of the plurality of small ladles, which results in high overhead. It has been impractical heretofore to utilize ladles of larger size as the large quantity of molten metal would radiate an excessive amount of heat, making it impossible for attendants to remain near enough to take care of the pouring operations. Furthermore, in view of the large capacity, the ladles could not be emptied rapidly enough to prevent solidification therein. In applications Serial Nos. 746,042 and 43,146, are disclosed means rendering the employment of large ladles entirely practical through the use of an insulated protecting cover. The present invention contemplates the use of an improved form of cover together with improved means for facilitating the opening and closing thereof.

One of the objects of this invention is to provide a ladle wherein the cover may be quickly moved from closed position to open position by a rearward pull thereon.

A more specific object of the invention is to provide in a device of the class described guiding means on the ladle and means on the cover co-operable with said guiding means for directing the cover upwardly and rearwardly in response to a rearward pull thereon.

A further object of the invention is to provide in a device of the class described means whereby the cover can be readily moved to and maintained in a position to expose the interior of the ladle, and means whereby when the ladle is manipulated in a particular manner, the cover can be entirely removed therefrom.

A more specific object of the invention is to provide in an improved ladle having a bail and having a cover movable to a position to expose the interior of the ladle, means on the cover and bail normally cooperable to limit the opening movement of the cover.

Other objects of the invention are to provide in a ladle:

Means for locking the cover in closed position.
Means for facilitating the application of manual force to the ladle cover during the opening and closing of the same.

Means for preventing the front edge of the cover from obstructing the attendant's view of the ladle spout during pouring.

Means for effectively insulating the cover.

With the above and other objects in view, the invention consists of the improved covered ladle and all its parts and combinations as set forth in the claims and all equivalents thereof.

In the accompanying drawing illustrating one complete embodiment of the preferred form of the invention:

Fig. 1 is a plan view of the improved ladle showing the cover in closed position, the full line position of the operating handle showing how said handle is used to move the cover, and the dot-and-dash line position of the cover handle showing how said handle is used to lock the cover in closed position;

Fig. 2 is a side elevational view of the ladle, the dot-and-dash lines showing the cover in open position;

Fig. 3 is a fragmentary sectional view taken on line 3—3 of Fig. 1; and

Fig. 4 is a side elevational view of the ladle illustrating how the cover can be entirely removed by tilting the ladle in a particular manner.

Referring more particularly to the drawing, the numeral 5 designates a ladle of desired form. In view of the fact that the ladles comprehended by the present invention are of relatively large size, it is desirable that the same be insulated, preferably in the manner disclosed in co-pending application, Serial No. 47,560.

The ladle is preferably formed with an up-standing circular rim 6, with a pouring spout 7 and with side trunnions 8. A bail frame 9 includes side bails having hook-shaped lower ends 10 for engagement with the trunnions 8, and an upper transverse bar 11.

Guiding members 12 which are preferably tubular in form, are suitably secured to upper side portions of the ladle as at 13 and 14, and said members are disposed in an inclined position as is clear from Fig. 2. One of the guiding members 12 may be provided with a tubular extension 15 for a purpose to be hereinafter described.

The ladle cover designated generally by the numeral 16, comprises a top disc of metal 17 and a surrounding depending flange 18. The front of the cover is preferably straight as at 19, and the rim 18 is tapered in the front as at 20 so that an operator standing at the rear of the ladle may at all times see the spout while pouring is being accomplished. If the rim portion 20 were 55

vertical, it would, in some positions, obstruct the attendant's view.

Welded to opposite sides of the cover toward the rear thereof are lateral extensions 21, and to each of these extensions one end of a rod 22 is rigidly secured. The rods normally extend at an incline corresponding to the incline of the guide tubes 12, said rods being slidable in the tubes as is clearly indicated in Fig. 2.

At the rear of the cover is a short section of horizontally disposed metal tubing 23, and a handle 24 having a projection 25 at its outer end which may be engaged with the tube 23 in the manner shown in Fig. 1, facilitates movement of the cover from the full line position of Fig. 2 to the dot-and-dash line position therein and vice versa. Inasmuch as it is desirable to normally limit the opening movement of the cover, the front of the latter is provided with an up-standing stop 26 which is engageable with the cross bar 11 of the bail frame, as shown in the dot-and-dash line position in Fig. 2.

It may at certain times be desirable to entirely remove the cover. In the present arrangement the parts are so arranged that when the ladle is tilted rearwardly as shown in Fig. 4, the stop 26 will fail to engage the cross bar 11, thereby permitting complete removal of the cover and complete withdrawal of the rods 22 from the guiding tubes 12.

The cover may also be formed with a projecting lug 27 having its outer end apertured as at 28. The lug is so positioned on the cover that when the cover is in the closed position shown in Figs. 1 and 2, the aperture 28 will register with the tubular extension 15 of the guiding member 12. When the cover is thus closed, the extension 25 of the handle 24 may be inserted into the aperture 28 and extension 15 to positively lock the cover in closed position; thus the handle 24 serves the dual purpose of facilitating movement of the cover and locking thereof.

The insulation of the ladle covers has occasioned considerable difficulty heretofore. Fire brick is a desirable insulating material, but when a fire brick is made of the exact size of the cover, it is found that the difference in coefficient of expansion between the metal forming the cover proper and the fire brick forming the lining therefore sets up stresses which result in breakage of the lining. Furthermore, due to the fact that these ladles and covers are furnished in a wide assortment of sizes, it is impractical and costly to have fire brick of the exact size and shape for each of the various sizes of covers.

By referring to Fig. 3, it may be seen that there is fire brick 29 inserted in the cover and that said brick is substantially less in diameter than the cover. The fire brick is also preferably formed with bevelled side edges 30 and with a plurality of recesses 31 in its lower face, communicating with bores 31' extending through the fire brick. In order to line a cover in the manner disclosed in the present invention, a thin layer 65 of fire clay is spread on the upper surface of the fire brick 29 and the brick is pressed against the inner surface of the cover top 17. Bolts 32 are then passed through the holes 31' in the fire brick and through registering apertures in the cover portion 17, the heads of the bolts being received in the recesses 31. Nuts 33 are then threaded on to the bolts and tightened to hold the fire brick in position. Next fire clay or other refractory material is packed while in plastic 70 condition between the edges of the fire brick and

the cover rim as at 34 and permitted to harden. Due to the bevel 30 on the fire brick, interlocking will take place between the edges of the fire brick and the hardened refractory material 34 to hold the two materials in position. After the 5 bolts are in place it is desirable to fill the recesses 31 with refractory material as at 35. It is also preferred to weld or otherwise secure a ledge 36 in position below the refractory material 34.

The joint formed at 30 between the fire brick 10 and the fire clay will permit a normal amount of expansion to take place in the lining without disrupting the cover. In addition, it will be noted that there is clearance between the sides of the bolt holes 31' and the bolts to allow for a certain amount of shifting of the fire brick during expansion thereof.

With this method of lining, it is apparent that one size of fire brick 29 may be readily adapted for use in various sizes of covers, it being merely 20 necessary to utilize more or less of the refractory material 34 as an edge filling.

It is apparent that the cover and associated mechanism permits the cover to be readily opened and closed by manipulation of the handle 24, 25 and that the cover can be further locked in position through use of the same handle. Due to the fact that the lower portion 37 of the cover rim overlaps the rim 6 of the ladle, it is apparent that a straight rearward sliding movement of 30 the cover to open the same would not function. Due however, to the use of the inclined guiding tubes 12 and cooperating inclined rods 22, it is apparent that the cover is simultaneously raised, so that the flange portions 37 clear the rim 6, 35 while the cover is being moved rearwardly.

Although only one form of the invention has been shown and described, it is apparent that various changes and modifications may be made without departing from the spirit of the invention, and all of such changes are contemplated as may come within the scope of the claims.

What we claim is:—

1. In combination, a ladle, a bail in connection with said ladle, a ladle cover, a slidable connection between the ladle and cover to provide for movement of the cover to a position to expose the interior of the ladle, and stop means projecting upwardly from the cover engageable with a portion of the bail when the cover has 50 been moved rearwardly a predetermined distance to limit the opening movement of the cover.

2. In combination, a ladle, a bail in connection with said ladle, a ladle cover, a slidable connection between the ladle and cover to provide for 55 movement of the cover to a position to expose the interior of the ladle, and stop means on the cover engageable with a portion of the bail to limit the opening movement of the cover when the ladle is in normal position, said stop means 60 being so positioned that when the ladle is tilted in a predetermined manner, the cover may be entirely removed.

3. In combination, a ladle, a cover therefor, guiding tubes secured to opposite exterior side 65 portions of the ladle and extending rearwardly therefrom, and rods projecting from opposite exterior side portions of the cover and slidable in said guiding tubes to provide for slidable opening of the cover by a rearward pull thereon.

4. In combination, a ladle, a cover therefor, guiding tubes secured to opposite exterior side portions of the ladle and extending at an angle rearwardly and upwardly, and inclined rods projecting from opposite exterior side portions of 75

the cover and slidable in said guiding tubes to provide for slidable opening of the cover by a rearward pull thereon.

5. In combination, a ladle, a cover therefor, guiding tubes secured to opposite exterior side portions of the ladle, rods projecting from opposite exterior side portions of the cover and slid-
10 able in said guiding tubes to provide for slidable opening of the cover, a tube extending vertically upwardly from the ladle, a lug projecting from the cover and having an aperture therein reg-
15 istrable with said vertical tube when the cover is closed, and means insertable in said aperture and vertical tube to lock the cover in closed position.

15. 6. In combination, a ladle, a cover therefor, a slidable connection between the ladle and cover to provide for movement of the cover to a position to expose the interior of the ladle, a separa-
20 ble cover operating handle, means on the cover with which said handle is engageable to open the cover, and other means with which said handle is interchangeably engageable to lock the cover in closed position.

7. In combination, a ladle having trunnions projecting laterally therefrom, a bail engageable with said trunnions to support said ladle for pivotal movement, a cover therefor, guiding means fixedly connected to said ladle above said trunnions and within said bail and extending at an angle rearwardly and upwardly at an angle to the plane of the cover also within said bail, and means on the cover cooperable with said guiding means on the ladle whereby the cover may be slidably moved on said fixed guiding means simultaneously rearwardly and upwardly without interference from said bail while being maintained in a plane substantially parallel to the plane of its ladle closing position, said guiding means and means on the cover being engageable
40 to maintain the cover in position when the ladle is tilted for pouring.

8. In combination, a ladle having trunnions projecting laterally therefrom, a bail engageable with said trunnions to support said ladle for pivotal movement, a cover therefor, and a slidable connection between the ladle and cover positioned exteriorly of the latter and to the side thereof to provide for movement of the cover to

a position to expose the interior of the ladle wherein a portion of the cover overhangs an exterior wall portion of the ladle, the slidable connection being disposed above the ladle trunnions and within the bail whereby the cover may be moved without interference from said bail.

9. In combination, a ladle having trunnions projecting laterally therefrom, a bail engageable with said trunnions to support said ladle for pivotal movement, a cover therefor, and an inclined slidable connection between the cover and ladle positioned exteriorly of the latter and to the side thereof and constructed to provide for movement of the cover simultaneously upwardly and rearwardly to a position to expose the interior of the ladle, the slidable connection being disposed above the ladle trunnions and within the bail whereby the cover may be moved without interference from said bail.

10. In combination, a ladle having a substantially circular top provided with a rim and having trunnions projecting laterally therefrom, a bail engageable with said trunnions to support said ladle for pivotal movement, a cover having flanges adapted to overlap said rim, and an inclined slidable connection between the ladle and cover positioned exteriorly of the latter and to the side thereof to provide for movement of the cover upwardly and rearwardly to expose the interior of the ladle wherein a portion of the cover overhangs an exterior wall portion of the ladle, the upward movement causing the cover flanges to clear the ladle rim, the slidable connection being disposed above the ladle trunnions and within the bail whereby the cover may be moved without interference from said bail.

11. In combination, a ladle having trunnions projecting laterally therefrom, a bail engageable with said trunnions to support said ladle for pivotal movement, a cover for said ladle, guiding tubes secured to opposite exterior side portions of the ladle above the trunnions and within the bail, and rods projecting from opposite exterior side portions of the cover and slidable in said guiding tubes to provide for slidable opening of the cover by a pull thereon.
